UNITED STATES PATENT OFFICE.

JOSEPH ZEITLIN, OF SOUTH KENSINGTON, LONDON, ENGLAND.

VACUUM-PUMP.

1,069,510.

Specification of Letters Patent. Patented Aug. 5, 1913.

Application filed March 19, 1910. Serial No. 550,458.

To all whom it may concern:

Be it known that I, JOSEPH ZEITLIN, a subject of the Emperor of Russia, residing at 5 Gilston road, South Kensington, in the county of London, England, engineer, have invented a certain new and useful Improved Vacuum-Pump, of which the following is a specification.

This invention relates to piston vacuum pumps and consists in certain improvements, the chief of which is the elimination of all clearance space at the end of the delivery stroke of the pump piston firstly by using an elastic connection between the piston and the actuating mechanism so that the piston can be driven against the end of the cylinder and secondly by providing an auxiliary piston or plunger which fills the port in the cylinder head through which the gases are expelled after the delivery stroke of the main piston has been completed.

In the production of very high and pure vacua, such as for example the vacuum required in incandescent electric lamp bulbs, it is necessary or advisable to inclose the pump or preferably two or more pumps connected in series, in an evacuated chamber and the invention will be hereinafter described with reference to a vacuum pump which is so inclosed, but it will be understood that in so far at any rate as the chief features of the improved pump are concerned, it may be applied to apparatus which is not so inclosed.

In the specification to United States Patent No. 905973 granted to the present applicant it is stated with reference to the multiple stage pump apparatus for the production of high vacua that by placing the high vacuum pumps in one vacuum chamber and the preliminary exhaustion pumps with the motor for driving all the pumps in a second vacuum chamber, the apparatus in the first chamber may be lubricated without the use of liquid lubricants so that the high vacuum chamber may be free from the vapor of such lubricants, but according to this invention the pump is so constructed that no lubricant of any sort whatever need be used for the pump cylinders or pistons or distributing valves and preferably also although not necessarily without any lubricant for any of the parts inclosed within the chamber aforesaid, the parts subject to rubbing friction being constructed so as to be substantially frictionless and immunity from leak-

age being obtained by making the leakage surfaces of great length. Further, special means are provided for eliminating the clearance space of the pump cylinders while leaving ample port area for the admission and discharge of the gases to be exhausted.

The invention further includes a doubly elastic connecting rod through which the pump pistons are actuated from a crank on a driving shaft, a link motion connecting the connecting rod with the pistons, a special mechanism for actuating the distributing valves, and special sealing devices to prevent leakage at the pipe connections and from the atmosphere to the chamber.

These and other improvements will be more particularly described with reference to the accompanying drawings which show a two cylinder series pump inclosed in a chamber which is itself exhausted by an auxiliary pump not shown in the drawings, Figure 1 being a sectional plan, Fig. 2 a vertical section taken on line II-II of Fig. 1, Fig. 3 a detail illustrating the valve actuating mechanism, Fig. 4 a part sectional elevation of the connecting rod (detached) and Fig. 5 is an elevation of the mechanism shown in Fig. 3.

In these drawings the pumps A, B inclosed in the casing or chamber C are driven from a shaft 1 extending through a special stuffing box in the casing and journaled in a pair of ball bearings 2, 3 of known kind one within and one outside the stuffing box. A belt pulley 4 on the outer end of the shaft provides means for driving the shaft from an electric or other suitable motor external to the casing. A ball washer 5 of known type is interposed between a collar fixed on the shaft and a suitable abutment on the casing to take any inward thrust to which the shaft may be subject. Leakage from the atmosphere along the shaft into the chamber C is prevented first by a stuffing box 6 filled with grease which is retained within the stuffing box by suitably shaped leather or dermatine packing members 6^a, 6^b, and secondly by one or more somewhat elongated sleeves 7 preferably of antifriction metal which closely fit around hardened enlargements 8 on the shaft which are ground to the bore of the sleeves. The sleeves 7 have their inner ends formed with annular bearing members or projections 7^a which are urged into close contact with the opposing carefully ground shoulders of the adjacent

enlargements or collars 8 on the shaft by means of springs 9. Secured between the sleeves 7 and the shell 10 of the stuffing box by means of washers 11, 12 are rings 13 of 5 dermatine or other suitable flexible non-porous material which does not deteriorate in contact with oil. The shell 10 of the stuffing box is suitably flanged and bolted with interposed packing over a correspondingly shaped opening in the casing C. The space between the dermatine rings 13 may if desired be connected with an auxiliary exhausting device to minimize the chance of leakage into the chamber C.

15 The shaft 1 is geared with a shaft 14 from which the pump pistons are driven by a crank 14^a through a linkage comprising a divided connecting rod the two parts 15, 16 of which are relatively movable in the direction of their axes and are correlated by means of a pair of springs 17, 18 which are compressed between follower plates 17^a, 17^b and 18^a, 18^b of which the plates 17^a, 18^a are adjustably secured on the part 16 of the 20 connecting rod, while the plates 17^b, 18^b are loose on this part of the rod and bear against suitably shouldered abutments on the part 15 of the rod. The part of the rod 16 marked 16^a which slides in a bush 15^a in the part 15 is of enlarged diameter for the reason afterward explained and to avoid any shake the bush 15^a is made equal or very slightly longer than the part 16^a. It will be seen that this connecting rod is substantially rigid so long as no axial force is applied exceeding that due to the compression of the spring that is for the time resisting the force being applied and that it will be extended or shortened as the case 30 may be when subjected to a greater force, the very slight difference in the lengths of the parts 15^a, 16^a being taken up by the almost inappreciable relative movement of the two parts of the connecting rod when 35 the latter is subject to a thrust or pull. The other spring that is to say the non-resisting spring, is rendered inoperative, as it abuts against the shoulder of the part 16^a.

The connecting rod 15, 16 couples the 50 crank 14^a with the end of an arm or crank 19 fixed on a rock shaft 19^a on which also is rigidly fixed a bell crank 19^b, 19^c. The crank arm 19^b is coupled indirectly with the main piston of pump B through the connecting rod 20 which is directly connected with an auxiliary piston or clearance plunger 21 the object of which will be herein-after explained. Similarly the crank arm 19^c is coupled indirectly with the main piston of pump A through link 22, bell crank 55 23 on rock shaft 23^a which is oppositely disposed to but is otherwise the duplicate of 19^b and 19^c, and connecting rod 20 which latter is directly coupled with the auxiliary piston 21 of pump A. The linkage connect-

ing the rock shaft 19^a with the two pistons is so designed that the oppositely moving pistons are always in substantial balance.

The auxiliary pistons 21 are mounted within the elongated cored bosses 24^a of the main pistons 24 within which they have a limited freedom longitudinally, the laterally extending pins 21^a at the lower end of the pistons 21 sliding in longitudinal slots 24^b in the sleeves 24^a. A spring 25 compressed between the main piston 24 and a follower plate 21^b carried by the pins 21^a tends to keep the auxiliary piston withdrawn into the boss 24^a as shown in pump B (Fig. 2), in which position the rear face 70 of the plate 21^b bears against a stop 26 on the end of the boss 24^a, with a small clearance left between the pins 21^a and the end of the slot 24^b. The auxiliary pistons 21 have projecting pieces 21^c which are shaped 75 to fill exactly the ports 27 in the cylinder head connecting the interior of the cylinders with the interior of the casings (preferably made integral with the cylinder head) of the distributing valves 28. The throw 80 of the crank 19 is designed to drive the main pistons 24 against the cylinder heads and thereafter, compressing the spring 25, to force the auxiliary pistons to close completely the ports 27, the pistons and their 85 actuating linkage remaining stationary in this position for a period during which the crank 14^a passes over the dead point.

The valve plugs 28 are oscillated intermittently so as to bring the suction ducts 28^a and discharge ducts 28^b into register with the ports 27 at the appropriate times by means of pinions 29 on the plug spindles 29^a which mesh respectively with two toothed wheels 30 gearing with each other and carried by stub shafts 30^a journaled in a bracket 31 integral with the pedestal of the crank shaft 14. The gear wheels 30 Figs. 3 and 5 are actuated intermittently by means of a tappet 32 on the crank shaft 14. As 90 the tappet rotates a projection 32^a on its free end is adapted to pass into and out of engagement successively with the projections 30^b on the faces of the gear wheels and turn the wheels as long as the tappet 95 projection 32^a and either of the projections 30^b, which may be in engagement with it, are moved along the same path. It will be seen by reference to Fig. 3 that during the periods of engagement the two wheels 30 100 will be rotated alternately in opposite directions and consequently the valve plugs with which the wheels 30 are geared will be oscillated intermittently. In order that this movement of the plugs should be accelerated the gear wheels 30 are connected by tension springs indicated by the arrows 33 105 which tend to turn the wheels inward toward each other in one direction or the other depending upon which side of the line 110

joining the center of the shafts 30^a the 5 springs lie. In the initial part of the movement of the gear wheels 30 by the tappet 32, the springs 33 are extended until their points of attachment are on the line joining the centers of the shafts 30^a. Soon after 10 passing this position, the wheels 30 complete the movement required to shift the valve plugs practically instantaneously under the action of the springs 33. Fixed stops 34 co-operate with a pin 35 projecting from one of the wheels 30 to limit the movement of the latter. The angular relation of the tappet 32 and the crank 14^a is such that the 15 movement of the wheels 30 by the tappet 32 begins a little before the crank 14^a passes the dead point and the whole movement of the valves is completed during the time that the main pistons and the auxiliary pistons 20 and their operating linkage are stationary and the double elastic connecting rod 15, 16 is being extended or shortened. In other words the angle through which the tappet 32 has to move in order that the shifting of 25 the valves should be begun and completed is less than the angle through which the crank 14^a sweeps during the period of inaction of the pistons. The suction duct 28^a of the valve of pump A is connected with the 30 vessel to be exhausted by a pipe 36 connected with an external stop cock 37 which is secured gas tight in the wall of the chamber C. The delivery duct 28^b of the valve of pump A is connected by a pipe 38 with the 35 suction duct 28^a of the other valve the delivery duct of which may open into the chamber C as shown or may be connected with the suction port of an external exhausting pump, or with an external evacuated space, by a pipe or duct 47 passing gas-tight through the wall of the chamber. 40

The valve plugs 28 are conical fitting in 45 conical sleeves 39 which have at their two ends cylindrical parts 39^a which house the ball bearings 40 on which the plugs 28 are mounted. Leakage at the junctions of the pipes 36, 38 and the valve plug spindles is prevented by means of a device similar to that already described in connection with 50 the shaft 1. At each of these junctions a spring 41 in compression between a fixed bracket or abutment 42 and a flange 43 on the ends of the pipes 36, 38 forces an annular bearing ring 43^a on the face of the flange 55 against the carefully ground face either of a fixed shoulder on the valve plug spindle 29^a, or, in the case of the suction end of the valve of pump A, of an extension piece or hollow nut 44 which is screwed on the end 60 of the spindle 29 against the flange 45^a of a sleeve 45 (with suitable interposed packing) which forms part of a double ball thrust washer of known type, the central washer 46 of which is rigid with the shell of the valve. 65 In assembling the parts the screw-threaded

end of the plug spindle 29^a is screwed into the sleeve 45 of the double ball thrust washer until the plug 28 is in sufficiently close contact with the shell 39 and the nut 44 is then screwed on the end of the spindle to lock the 70 parts. A similar double ball thrust washer is provided at the delivery end of the valve pump B. By providing the plug valves with ball thrust washers as described the adjustment of the plug is accurately maintained in spite of any unbalanced force acting in an axial direction on the plugs. 75

Apart from the special anti-leakage devices hereinbefore described the tendency to leakage is minimized by lengthening the 80 leakage surfaces as much as possible, this being of course particularly necessary in the case of the pistons both main and auxiliary, neither of which are lubricated either with oil or even any dry lubricant, the small difference of pressure on the two sides of the piston due to the use of the evacuated chamber enabling a comparatively frictionless piston to be used and lubrication dispensed with. The fixed joints, such as the covers 85 of the chamber and of the cylinders may be made in any suitable known manner. 90

Having thus described the nature of my said invention and the best means I know of carrying the same into practical effect, I 95 claim:—

1. In vacuum pumps, a pump cylinder, a port in the cylinder end, a main piston within the cylinder, an auxiliary piston mounted within the main piston and having an end 100 shaped to fit exactly the said port, means normally operating to cause the auxiliary piston to enter the main piston to a desired extent and means for driving said pistons simultaneously and moving the auxiliary 105 piston independently of and further than the main piston so that the said end of the auxiliary piston fills the port after the main piston has been driven against the cylinder end. 110
2. In a pump, a driving shaft, a pump cylinder having a single port in its head serving as an inlet and exhaust port, a main piston, an auxiliary piston movably mounted within the main piston having an end shaped 115 to fit exactly the port in the cylinder, an elastic driving connection between the shaft and one of the pistons operating to drive the main piston forward against the cylinder head and to cause the end of the auxiliary 120 piston to fill the port at the completion of the forward or delivery stroke and means interposed between the main and auxiliary pistons and adapted to retain the latter entirely withdrawn within the former until 125 the main piston completes its delivery stroke. 130
3. In apparatus for producing a high vacuum, a driving shaft, a pump cylinder, a port in the cylinder end, a main piston within the cylinder, an auxiliary piston mounted

within the main piston, a driving connection elastic in one direction between the said pistons, a doubly elastic driving connection between the driving shaft and one of the pistons whereby the main piston may be driven against the end of the pump cylinder and means for projecting the head of the auxiliary piston so as to fill the said port for an appropriate period after the main piston has completed its delivery stroke.

4. In apparatus for producing a high and pure vacuum in a vessel, a casing forming a closed chamber, a driving shaft extending through the wall of the casing into the chamber, a pump cylinder inclosed in the chamber and having a single port serving for induction and exhaust purposes and adapted to be connected alternately with the vessel and with the chamber, a main piston in the cylinder, mechanism for actuating the piston, an elastic connection between the main piston and the actuating mechanism whereby the piston may be driven forward against the cylinder end, an auxiliary piston mounted within the main piston, means for projecting the head of the auxiliary piston so as to fill the said port for an appropriate period after the main piston has completed its forward movement, and a driving connection between the actuating mechanism and the driving shaft.

5. In apparatus for producing a high and pure vacuum in a vessel, a casing forming a closed chamber, a driving shaft extending through the wall of the casing into the chamber, a pump cylinder inclosed in the chamber and having a single port serving for induction and exhaust purposes and adapted to be connected alternately with the vessel and with the chamber, a main piston in the cylinder, a crank shaft within the chamber, linkage for actuating the piston, a doubly elastic driving connection between the crank shaft and the linkage whereby the piston may be driven forward against the cylinder end, an auxiliary piston mounted within the main piston, means for projecting the head of the auxiliary piston so as to fill the said port for an appropriate period after the main piston has completed its forward movement, and a driving connection between the crank shaft and the driving shaft.

6. In a vacuum pump the combination of a pump cylinder, a main piston in the cylinder, an auxiliary piston mounted with a limited freedom longitudinally within the main piston, and means for driving the main piston through the auxiliary piston.

7. In apparatus for producing a high and pure vacuum in a vessel, a casing forming a closed chamber, a driving shaft extending through the wall of the casing into the chamber, a pump cylinder inclosed in the chamber and having a single port serving for induction and exhaust purposes and adapted to

be connected alternately with the vessel and with the chamber, an elongated main piston in the cylinder, an auxiliary piston mounted within the main piston with a limited freedom longitudinally, a driving connection elastic in one direction between the said piston whereby the head of the auxiliary piston may be projected beyond the head of the main piston for filling the said port, a crank shaft within the chamber and coupled with the driving shaft, a crank on the crank shaft, linkage for actuating the auxiliary piston, and a doubly elastic driving connection between the crank and the linkage to permit the main piston to be driven forward against the cylinder end and to remain stationary for a period during which the crank passes over a dead point.

8. In apparatus for producing a high vacuum, a plurality of pump cylinders connected in series, a port in the end of each cylinder, a valve shell attached to each cylinder's end, an oscillating valve plug movably mounted in each shell having a suction duct and delivery duct adapted to communicate with the respective cylinder port, and means for rotating the valve plug intermittently and alternately in opposite directions so that the ducts therein register with the respective cylinder ports.

9. In apparatus for producing a high and pure vacuum in a vessel, a casing forming a closed chamber, a driving shaft extending through the wall of the casing into the chamber, a plurality of pump cylinders in the chamber and connected in series, a port in the end of each cylinder, a valve shell at the end of each cylinder, an oscillating valve plug movably mounted in each valve shell having a suction duct and a delivery duct adapted to communicate respectively and successively with the corresponding cylinder port, an elongated piston in each cylinder, mechanism for actuating the pistons for withdrawing air or gas from the vessel and for delivering the air or gas into the chamber, a device for oscillating the valve plugs, and a driving connection coupling the actuating mechanism and the oscillating device to the driving shaft.

10. In apparatus for producing a high and pure vacuum in a vessel, a casing forming a closed chamber, a driving shaft extending through the wall of the casing into the chamber, a plurality of pump cylinders in the chamber and connected in series, a port in the end of each cylinder, a valve shell at the end of each cylinder, an oscillating valve plug movably mounted in each valve shell having a suction duct and a delivery duct adapted to communicate respectively and successively with the corresponding cylinder port, an elongated piston in each cylinder, a crank shaft, a rock shaft, a doubly elastic driving connection between the crank shaft

5 and rock shaft, linkage connecting the said rock shaft and the pistons and adapted to cause the pistons to move simultaneously in opposite directions, a device for oscillating the valve plugs, and a driving connection coupling the crank shaft and the oscillating device with the driving shaft.

10 11. In apparatus for producing a high vacuum, a casing forming a closed chamber, a pair of pump cylinders, a pair of pistons comprising a main and an auxiliary piston in driving connection with each other in each cylinder, the pairs of pistons being arranged in opposite phases with respect to each other, a driving shaft extending through the wall of the casing into the chamber, a crank shaft in the chamber in geared connection with the driving shaft, a rock shaft mounted within the chamber, a 15 crank on the rock shaft, a doubly elastic connecting rod coupling the crank shaft and the crank on the rock shaft, a two-arm bell crank fixed to the rock shaft, a connecting rod coupling one arm of the bell crank with one of the auxiliary pistons, a second rock shaft within the chamber, a second two arm bell crank fixed to the second rock shaft, a second connecting rod coupling one arm of the second bell crank to the other auxiliary 20 piston, and a link connecting the second arm of the first bell crank with the second arm of the second bell crank.

25 12. In apparatus for producing a high vacuum comprising one or more pumps inclosed in a chamber, which pumps are actuated by a driving shaft and have each a conical distributing valve plug provided with suction and discharge ducts adapted to be brought into register with a port in the respective pump cylinders connected therewith, a pair of toothed wheels mounted within the chamber intermediate of the plug spindles and gearing with each other, a pinion on each plug spindle meshing respectively with the toothed wheels and means 30 coupled with the driving shaft for rotating the said toothed wheels intermittently and alternately in opposite directions whereby the said suction and discharge ducts are brought into register with the respective cylinder port.

35 13. In apparatus for producing a high vacuum comprising one or more pumps inclosed in a chamber, which pumps are actuated by a driving shaft and have each a conical distributing valve plug provided with suction and discharge ducts adapted to be brought into register with a port in the respective pump cylinders connected therewith, a pair of toothed wheels mounted within the chamber intermediate of the plug spindles and gearing with each other, a pinion on each plug spindle meshing respectively with the toothed wheels, a projection 40 on the face of each wheel, a second shaft

coupled with the driving shaft, and a tappet carried by the second shaft and adapted to engage successively the said projections and thereby rotate the said toothed wheels and valve plugs intermittently and alternately in opposite directions so that the said suction and discharge ducts are brought into register, respectively, with a cylinder port.

45 14. In apparatus for producing a high vacuum comprising two pumps inclosed in a chamber, which pumps are actuated by a driving shaft and have each a conical distributing valve plug provided with suction and discharge ducts adapted to be brought into register with a port in the respective pump cylinders connected therewith, a pair of toothed wheels mounted within the chamber intermediate of the plug spindles and gearing with each other, a pinion on each plug spindle meshing respectively with the toothed wheels, a projection on the face of each wheel, a second shaft coupled with the driving shaft, a tappet carried by the second shaft and adapted to engage successively the said projections and thereby rotate the said toothed wheels and valve plugs intermittently and alternately in opposite directions so that the said suction and discharge ducts are brought into register, respectively, with a cylinder port and means whereby the rocking movements imparted to the plugs may be accelerated with respect to the rotary movement of the driving shaft.

50 15. In apparatus for producing a high vacuum comprising a pump provided with a distributing valve plug having a screw-threaded spindle, the plug being mounted in a shell and co-operating with a port in the end of the cylinder, means for positively adjusting the plug in an axial direction with respect to the shell and fixing the same in position, comprising a double thrust washer mounted immovably in an axial direction within the shell and internally threaded for the adjustable reception of the said spindle and a nut in screwing adjustment on the said spindle and adapted to be screwed into locking engagement with the washer.

55 16. In apparatus for producing a high and pure vacuum, a casing forming a closed chamber, a piston pump within the chamber, mechanism for actuating the pump piston, a driving shaft provided with a plurality of enlargements forming shoulders thereon, the said shaft extending through the wall of the casing in the chamber, a driving connection between the driving shaft and the actuating mechanism, and a device for preventing leakage of air or gas into the chamber along the shaft comprising a stuffing box 115 surrounding the shaft, annular packing members for retaining grease within the stuffing box, a plurality of elongated sleeves fitting the said shaft enlargements, and springs interposed between the wall of the 120

stuffing box and the sleeves and adapted to press the sleeves against the said shoulders.

17. In apparatus for producing a high and pure vacuum, a casing forming a closed chamber, a piston pump within the chamber, mechanism for actuating the pump piston, a driving shaft provided with a plurality of enlargements forming shoulders thereon, the said shaft extending through the wall of the casing in the chamber, a driving connection between the driving shaft and the actuating mechanism, and a device for preventing leakage of air or gas into the chamber along the shaft comprising a stuffing box surrounding the shaft, annular packing members for retaining grease within the stuffing box, a plurality of elongated sleeves fitting the said shaft enlargements, springs interposed between the wall of the stuffing box and the sleeves and adapted to press the sleeves against the said shoulders, flexible rings interposed between the

said sleeves and the wall of the stuffing box and washers interposed between the stuffing box wall and the sleeves and adapted to retain the rings in proper position. 25

18. In apparatus for producing a high vacuum, a driving shaft, a pump cylinder, a port in the cylinder end, a main piston within the cylinder, an auxiliary piston mounted within the main piston, a driving connection elastic in one direction between the said pistons and means for projecting the head of the auxiliary piston so as to fill the said port for an appropriate period 30 after the main piston has completed its delivery stroke. 35

In testimony whereof I have signed my name to this specification in the presence of two subscribing witnesses.

JOSEPH ZEITLIN.
